UNITED STATES PATENT OFFICE

2,529,881

SNAP SWITCH HAVING A BLADE
TORSIONALLY MOUNTED

Edwin August Miller, Fairfield, Conn.

Application November 19, 1947, Serial No. 786,835

3 Claims. (Cl. 200—67)

1

This invention relates to cantilever type of switch blade; its free end having a marginally fixed extremity provided with a weakened central portion normally in the plane of the blade.

The objects of the invention are to provide a switch blade having integrally therewith a marginally fixed end with a centrally yielding portion in relative lateral alignment with said fixed portion; to provide a base support to which the fixed portion of said extremity is secured; and to provide for such support a rigid arm to which the free extremity of a compression arm is hinged intermediate the length of the blade.

With reference to the accompanying drawing, the Figure 1 is a plan view of switch blade the fixed extremity of which is marginally supported by a base and illustrating a central twistable portion of said extremity movably carried with said blade; Figure 2 is a side elevation of the device illustrating the blade in one position relative to spaced stops; Figure 3 is a side elevation similar to that of the next previous figure but illustrating the blade in a different position relative to said stops; Figure 4 is a fragmentary side elevation of the device illustrating an exaggerated position of said blade with reference to said twistable portion of the fixed extremity thereof, and also illustrating opposing blade operating means, a dotted actuator being illustrated in engagement with an extension at the rear of the blade thereby eliminating one of said opposing actuators; and Figure 5 is a rear elevation of the device exposing a yoke support for marginal support of fixed extremity of the blade.

With more particular reference to the accompanying drawing, the numeral 1 designates the switch blade carrying at its free extremity the contact 2. The blade 1 is provided with marginally positioned companion compression arms 3 and 4 carried by said free extremity the free ends 5 and 6 of said compression arms 3 and 4 extend midway the length of a central tension arm 7 of the blade 1 and laterally spaced therefrom. The extremity 8 of the tension arm 7 is marginally supported by means of a solid yoke 9 having the upright and relatively spaced pedestals 10 and 11 upon each of the tops of which the extremity 8 is marginally secured. Centrally, the extremity 8 is provided with a weakened portion 8A by means of cut-out portions at 12 upon both sides of an elongated reinforcing rib formation 13 rigidly extending into the tension arm 7 so that the weakened portion 8A is integrally connected therewith.

The solid yoke support 9 is provided with a

2

pair of rigid arms 14—15 extending intermediate the length of the device. At the free end of each rigid arm 14—15 there is integral therewith a turned-up extremity 14A and 15A of which each the under-surface 14B and 15B is provided with an arcuate depression or notch 14C or 15C within each of which a free extremity 5 or 6 of a companion compression arm 3 or 4, respectively, is received and held under compression.

An actuator 16 movable down upon the switch blade 1 to assist in moving its free extremity carrying the contacts 2 and 2A from one to the other of relatively spaced stops 17—18.

In operation, the actuator 16 is pressed, manually or otherwise, down upon the switch blade 1 by which the contacts 2 and 2A are carried at the free extremity, the contact 2 being normally in engagement with the stop 17. The pressed actuator 16 immediately distorts the tension blade 1 as the cantilever force overcomes the compression arms 3 and 4 and snaps the free contact carrying extremity of the tension blade 1 from the stop 17 to the other stop 18, the breaking of the contact 2 from the stop 17, and the engagement of the contact 2A with the stop 18 being a sudden movement of snap-acting propensity to which the twistable weakened portion 8A greatly contributes thus eliminating all stiff opposition to the action of the blade.

While the engagement of the contact 2A with the stop 18 is illustrated as a momentary one yet, if it is desired that contact engagement be a maintained one until a reversed operation is had, the opposing actuators 16 and 16A, as illustrated by the Figure 4, may be provided. Also, if opposing actuators 16 (and 16B, shown in dotted lines) both engageable at the top surface of the blade 1 which may have the rear extension 1A, the actuator 16A may be omitted.

Of course, the structure of the blade 1, illustrated as having marginally positioned compression arms 3—4 and a central tension arm 7, is susceptible of change wherein the tension member may be the familiar blade with an elongated opening therethrough within which a tongue provides the compression member.

I claim:

1. A switch blade associated with a base support and comprising a cantilever type of tension member having a free extremity and a portion engageable by an actuator for assisting the movement of said free extremity from one to another of relatively spaced stops provided by said base; substantially wide transversal extensions provided

by said tension member at the rear thereof, each of said extensions being secured upon one of two pedestals provided by said base support and each extension having a neck of lesser width than that of said extensions to provide for said tension member a weakened twistable connection between said pedestals; a reinforcing rib formation at said tension member and extending longitudinally therewith in both directions beyond said weakened connection; and compression arms, each having an end carried adjacent the forward end of said tension member and a rear end held under compression by a portion of said supporting base intermediate the length of said tension member, said compression arms thus held having looped portions out of the plane of said tension member, an acting engagement by said actuator distorting the tension member as the cantilever force overcomes the compression arms and snaps the said free extremity of the tension member from one to the other of said stops. 20

2. A switch blade associated with a base and comprising a cantilever type thereof providing a tension member having a free extremity and a portion engageable by an actuator for assisting the movement of said free extremity from one to another of relatively spaced stops provided by said base; transversally extended portions provided by said tension member at the rear thereof, each of said extended portions being secured to one of spaced apart portions of said base; and compression arms, each having an end carried adjacent the forward end of said tension member and a rear end held under compression by one of said spaced apart base portions intermediate the length of said tension member, said compression arms thus held having looped portions out of the plane of said tension member, an acting engagement by said actuator distorting the tension 35

member as the cantilever force overcomes the compression arms and snaps the free extremity of the tension member from one to the other of said stops.

- 5 3. A switch blade associated with a base and comprising a cantilever type thereof providing a tension member having a free extremity and a portion engageable by an actuator for assisting the movement of said free extremity from one to another of relatively spaced stops provided by said base; transversally extended portions provided by said tension member at the rear thereof, each of said extended portions being secured to one of spaced apart portions of said base; and a compression arm having an end carried by the forward end of said tension member and a rear end held under compression by a forwardly extending portion of said base intermediate the length of said tension member, said compression arm having a looped portion out of the plane of said tension member, an acting engagement by said actuator distorting the tension member as the cantilever force overcomes the compression arm and snaps the free end of the tension member from one to the other of said stops. 25
